Primary Examiner — Joseph Kukella*Assistant Examiner* — Heather Wencl(74) *Attorney, Agent, or Firm* — Victor H. Segura(57) **CLAIM**

The ornamental design for an exit warning light, as shown and described.

DESCRIPTION

FIG. 1 is a front-side perspective view of the exit warning light;

FIG. 2 is a front view thereof;

FIG. 3 is a bottom view thereof;

FIG. 4 is a top view thereof;

FIG. 5 is a back view thereof;

FIG. 6 is a left side view thereof; and,

FIG. 7 is a right side view thereof.

The broken lines in the drawings depict portions of the exit warning light that form no part of the claimed design.

1 Claim, 4 Drawing Sheets
